Primary Examiner — Vy Koenig(74) *Attorney, Agent, or Firm* — Leanne Taveggia Farrell; Westman, Champlin & Koehler, P.A.**(57) CLAIM**

The ornamental design for a chair, as shown and described.

DESCRIPTION

FIG. 1 is a back perspective view of a chair showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The dash-dash-dash broken lines shown in the drawings are included for purposes of illustrating portions of the chair that form no part of the claimed design. The long dash-short dash lines included at the angle corners on the top and bottom of the chair represent a boundary of the claim that form no part of the claimed design.
